Edward N. Carpenter, Atty.

UNITED STATES PATENT OFFICE.

PHILLIP T. MACGOWN, OF MYSTIC, CONNECTICUT.

BOOT OR SHOE.

1,246,630.

Specification of Letters Patent.

Patented Nov. 13, 1917.

Application filed December 29, 1916. Serial No. 139,439.

To all whom it may concern:

Be it known that I, PHILLIP T. MACGOWN, a citizen of the United States, residing at Mystic, in the county of New London and 5 State of Connecticut, have invented certain new and useful Improvements in Boots or Shoes, of which the following is a specification.

My invention relates to boots and shoes 10 and particularly to the construction of counter stiffeners such as are incorporated in the heels thereof.

With the ordinary boot or shoe, particularly if it fits the foot more or less loosely, 15 the heel of the foot and of the stocking or sock covering the same, move up and down against the back portion of the shoe during each step of the wearer which results in injury to the heel of the foot and also the heel 20 portion of the stocking or sock. The object of my invention is to obviate this objectionable feature and to provide an improved counter stiffener for boots and shoes which, when incorporated therein, accomplishes this 25 end.

In the accompanying drawings:

Figure 1 is a sectional view of the heel portion of a shoe constructed in accordance with my invention.

30 Fig. 2 is a side elevation of a boot or shoe counter stiffener constructed in accordance with my invention.

Fig. 3 is a partial side elevation of the forward end of the outer member herein- 35 after described.

Fig. 4 is a partial side elevation of the forward end of the inner member herein- after described.

Fig. 5 is a section on line 5—5 of Fig. 2. 40 Fig. 6 is a section on line 6—6 of Fig. 3.

Fig. 7 is a section on line 7—7 of Fig. 4.

Fig. 8 is a perspective view of another 45 form of my invention. Fig. 9 is a longitudinal sectional view of the counter stiffener shown in Fig. 8. Fig. 10 is a section on line 4—4 of Fig. 9.

My improved counter stiffener comprises two counter-shaped parts A and B made from any suitable sheet material, preferably 50 sheet metal, the part A being made at its bottom with an inturned flange α and the part B being made at its bottom with an in- turned flange β overlying the flange α of part A.

55 Near their forward ends the two parts A and B are pivotally fastened together as at

C and D. As shown in Figs. 1 to 7, inclusive, each side of member B is provided near its forward end and upon its outer side with a stud c' formed at its free end with a mutilated head or flange c^2 , while each side of member A is formed near its forward end with a hole c^3 through which the adjacent stud c' extends. The hole c^3 is of the same shape as the head or flange c^2 but when the 60 two parts A and B occupy their normal relative positions the hole is out of register with the flange c^2 so that the latter overlies the portion of member A adjacent hole c^3 thereby locking the two members together. The 65 flange c^2 overlies the material of member A at the side of hole c^3 sufficiently to permit of limited relative swinging movement of the two members without disconnecting them or bringing the flange into register 70 with the hole.

Preferably the member A is formed adjacent each hole c^3 with a recess c^4 to receive the flange or head c^2 so that the outer end of the stud c' does not project beyond 80 the outer surface of member A. The side of this recess c^4 also cooperates with the stud to hold the latter against lateral displacement in hole c^3 .

The two members A and B are assem- 85 bled by placing the member B within the member A with its rear portion relatively elevated, inserting the studs c' in holes c^3 and lowering the rear portion of member B.

The counter stiffener constructed as above 90 described is incorporated in the heel of a boot or shoe as shown in Fig. 1 with the outer member A interposed between the upper F and lining G, and the inner member B inside of the lining G so as to directly receive 95 the heel of the foot, the pivotal connections C and D being so located that the back portion of the inner member B is held from pressing against the back of the shoe. The flange α of member A is placed, together 100 with the lower edges of the upper and its lining, between the innersole H and outersole I, as usual, and the heel attaching nails J are driven through said flange as is the case with the usual counter stiffener.

The flange β of the inner member B rests on top of the innersole H so that a portion of the heel of the foot rests thereon and tends to hold said member in its lowermost position against the innersole. When the 110 heel of the foot slides up and down within the shoe the frictional engagement between

the heel of the stocking or sock and the interior of the member B causes the latter to swing on its pivots C and D with the heel thus relieving and shielding the latter from 5 sliding engagement with the heel portion of the shoe and obviating the objections to the ordinary boot or shoe pointed out above.

In order to increase the frictional adherence between the stocking or sock and the 10 inner member B, the latter may have its inner surface covered by a lining b' of felt, cloth or other appropriate material, fastened thereon by cement or other suitable means.

In the form of my invention shown in 15 Figs. 8, 9 and 10 A' is the outer counter stiffener member and B' the inner heel receiving member which in this instance is pivotally connected as at C' and D' to the member A' by means of studs, a thin washer E of any 20 suitable material, preferably sheet metal, being interposed between each pair of pivotally connected ends to hold the two parts A' and B' out of contact and provide between them a thin space to accommodate the lining 25 of the shoe.

What I claim is:

1. A boot or shoe having a counter shaped heel receiving member arranged upon the interior of the heel portion thereof, and means 30 pivotally connecting the forwardly extending ends of said member to the sides of the shoe.

2. A boot or shoe having a counter shaped heel receiving member arranged upon the 35 interior of the heel portion thereof, and means pivotally connecting the forwardly extending ends of said member to the sides of the shoe so as to provide for movement thereof with the heel of the foot and hold 40 said member out of movement retarding engagement with the back of the shoe.

3. As a new article of manufacture, a counter stiffener for boots and shoes having a counter shaped heel receiving member arranged 45 within it, and means pivotally connecting the forward ends of said member to the sides of the counter stiffener.

4. As a new article of manufacture, a counter stiffener for boots and shoes having

a counter-shaped heel-receiving member arranged within it; and means pivotally connecting the forward ends of said member to the sides of the counter stiffener so as to leave a lining accommodating space between 50 said stiffener and member.

5. In a boot or shoe, in combination, a counter stiffener disposed between the lining and upper; a counter shaped heel receiving member upon the interior of the lining and arranged within said stiffener, 60 and means pivotally connecting the forward ends of said member to the stiffener so as to provide for swinging movement of said member with the heel of the foot.

6. As a new article of manufacture the 65 combination with a counter stiffener for boots and shoes, of a member arranged within said stiffener and shaped to fit the heel of a foot, and means pivotally connecting the forward ends of said member to the sides of 70 the counter stiffener.

7. In a boot or shoe, the combination with the counter stiffener thereof, of a member arranged within said stiffener and shaped to fit the heel of a foot, and means pivotally 75 connecting the forward ends of said member to the sides of the counter stiffener so as to provide space between said stiffener and member for the lining of the boot or shoe and hold said member out of movement retarding 80 engagement with said lining.

8. As a new article of manufacture a counter stiffener for insertion between the lining and upper of a shoe; a counter-shaped member arranged within said counter stiffener 85 adapted to occupy a position inside of the lining, and means pivotally connecting the forward ends of said members, said means consisting of a pair of studs on one of said members each made at its free end with a 90 segmental flange and a pair of segmental holes formed through the forward ends of the other member to receive said studs and which are normally out of register with the segmental flanges of the studs.

In testimony whereof I have affixed my signature.

PHILLIP T. MACGOWN.
